UNITED STATES PATENT OFFICE

164,263

DEVELOPER-PRINTER

Julius Reader, Chicago, Ill., assignor to American Photocopy Equipment Company, Chicago, Ill., a limited partnership

Application April 28, 1951, Serial No. 14,999

Term of patent 14 years

(Cl. D61—1)

To all whom it may concern:

Be it known that I, Julius Reader, a citizen of the United States, and resident of Chicago, in the county of Cook and State of Illinois, have invented a new, original, and ornamental Design for a Developer-Printer, of which the following is the specification, reference being had to the accompanying drawing, forming a part hereof.

Fig. 1 is a top plan view of a developer-printer showing my new design.

Fig. 2 is a front elevational view thereof.

Fig. 3 is a view of one end thereof.

Fig. 4 is a back elevational view thereof.

Fig. 5 is a view of the other end thereof.

I claim:

The ornamental design for a developer-printer, substantially as shown.

JULIUS READER.
